UNITED STATES PATENT OFFICE.

ERNEST LYNN, OF BEAVER FALLS, PENNSYLVANIA.

METHOD OF MAKING METAL REEDS FOR WIND INSTRUMENTS.

1,133,868.

Specification of Letters Patent. Patented Mar. 30, 1915.

Application filed April 29, 1914. Serial No. 835,142.

To all whom it may concern:

Be it known that I, ERNEST LYNN, a citizen of the United States, residing at Beaver Falls, in the county of Beaver and State of Pennsylvania, have invented certain new and useful Improvements in Methods of Making Metal Reeds for Wind Instruments, of which the following is a specification.

This invention relates to a method of making metal reeds for wind instruments such as clarinets, saxophones, or other musical instruments wherein are employed reeds sounded by the passing air.

This invention has for its object the formulation of a method of making a reed of metal whereby it has been found in practice a particularly superior tone is produced and the life of the reed rendered substantially permanent, or, at least indefinitely extended.

Of the accompanying drawings, Figure 1 represents the mouthpiece of a clarinet having this invention applied thereto. Fig. 2 is a plan view of this invention detached. Fig. 3 is a side view, and Fig. 4 is a cross-section on the broken line $\alpha-\alpha$ of Fig. 2.

Throughout the drawings and description, the same letter is used to refer to the same part.

Considering the drawings, the clarinet A has a mouthpiece B, provided with the clamping devices C constructed to secure the reed D. The reed is composed of metal. As shown, it has a relatively thick and rigid end portion E, decreasing gradually into the flat, thin, and flexible end F, which forms the tongue or vibrating end of this invention. In practice, the thin end F is not greatly thicker than a piece of thin card-board such as visiting cards are made from. The thickness is approximately one-fiftieth of an inch.

In making this invention the thicker end E, that has usually a rounded upper surface and a flat lower surface as shown in Fig. 4, is formed, and then the thin end portion is formed of different density by hammering it repeatedly. The continued hammering increases the density of the metal, and produces a most excellent result particularly with aluminum. The metal may be softened by heat and then subjected to the hammer-

ing, but, I do not limit my invention to the employment of heat, for the reason that the result may be accomplished by hammering cold metal.

It will be understood that the hammering action is not an unlimited or unregulated step in this method. With a given piece of metal, after a certain hammering, an instrumental trial is made of the reed. The object is to bring each reed by hammering and testing up to the precise condition wherein the certain quality of musical sound desired is attained. Excessive hammering injures the quality of the sound, and it is not commercially practicable to bring the reed back to quality after too much hammering. The word "quality" in this description is not intended to mean the pitch, but rather the timber of the musical sound. This invention cannot be made by rolling or pressing. Again, when another piece of metal is taken up for hammering, it may, by reason of its different nature, call for more hammering or less before it will create the exact quality of sound. Through repeated hammering, and musically testing each reed on an instrument, the reed is brought into the condition required.

It is customary to construct this invention as shown in Figs. 2 and 3, the lower side being flat and uninterrupted from end to end, and the thin end portion flat on both sides.

The operation of this invention is precisely the same as the use of the ordinary reed for wind instruments and need not be explained in detail. Reeds made in accordance with this invention are given a smooth external surface, they cannot become water-soaked, they cannot warp, dry out and crack, they are practically indestructible, and may be so readily cleansed as to be almost perfectly sanitary.

Having now described this invention and the method of making it, what I claim is:

1. A method of making metal reeds for wind instruments, the said reeds comprising each a rigid end portion and a thin flexible end portion, the said method consisting in hammering the said thin end portion to increase the density and to modify the elasticity, and in musically testing the same, and

in repeating the said hammering and testing until a desired quality of tone is obtained.

2. A method of making metal reeds for wind instruments, consisting in heating one end of a piece of metal and forming that end into a thin flexible portion, and in hammering the said thin end portion to increase the density and to modify the elasticity, and

in musically testing the same, and in repeating the said hammering and testing until a desired quality of tone is obtained.

In testimony whereof I affix my signature in presence of two witnesses.

ERNEST LYNN.
